CLAIM

The ornamental design for a treadmill, as shown and described.

DESCRIPTION

FIG. 1 is a perspective view of a treadmill showing our new design;

FIG. 2 is a front end elevational view of the treadmill of FIG. 1;

FIG. 3 is a rear end elevational view of the treadmill of FIG. 1;

FIG. 4 is a right side elevational view of the treadmill of FIG. 1;

FIG. 5 is a left side elevational view of the treadmill of FIG. 1; and,

FIG. 6 is a top plan view of the treadmill of FIG. 1, the bottom of the treadmill is unornamented and forms no part of the claimed design.

1 Claim, 5 Drawing Sheets
